(57) **CLAIM**

The ornamental design for a medical instrument, as shown and described.

DESCRIPTION

1.1 is a top view of a medical instrument, showing our new design;

1.2 is a bottom view thereof;

1.3 is a right side view thereof;

1.4 is a front view thereof;

1.5 is a left side view thereof;

1.6 is a rear view thereof;

1.7 is a top, front and left side perspective view thereof; and

1.8 is a bottom, rear and right side view thereof.

The surface markings shown in broken lines on the top surface in 1.1 and 1.7 form no part of the claimed design.
